UNITED STATES PATENT OFFICE.

JOHN F. MAHLSTEDT, OF LOS ANGELES, CALIFORNIA.

PRINTING-MACHINE.

1,130,991.

Specification of Letters Patent.

Patented Mar. 9, 1915.

Original application filed July 29, 1913, Serial No. 781,750. Divided and this application filed January 18, 1914. Serial No. 812,960.

To all whom it may concern:

Be it known that I, JOHN F. MAHLSTEDT, a citizen of the United States, residing at Los Angeles, in the county of Los Angeles and State of California, have invented a new and useful Printing-Machine, of which the following is a specification.

This application is a division of a former application of mine filed July 29th, 1913, Serial No. 781,750, for printing machine, adapted for printing letters, circulars and the like, with the heading of the letter in ordinary printing ink of any preferred color, the body of the letter being printed with an inked ribbon to imitate typewriting, while the signature of the letter may be printed with ink to give the effect of writing.

The present application relates to inking features.

Referring to the drawings: Figure 1 is a vertical longitudinal section through the receiving end of the machine. Fig. 2 is a plan view of what is shown in Fig. 1, with the ink fountain and ink disk removed. Fig. 3 is a plan view of the ink fountain. Fig. 4 is a section on line x^4-x^4 , Fig. 1. Fig. 5 is a side elevation of the coupling between the ink plate and its operating shaft. Fig. 6 is a perspective in detail of the shaft which operates the ink plate.

Secured to the bed 2 is a chase 13 containing type 14, which print the body of the letter, and type 15, which print the heading of the letter. Type 14 which print the body of the letter print through a ribbon 16, so that the body of the letter appears as if it were written on a typewriter, while the type 15 are inked directly by a roller 17 so that the heading of the letter appears as though regularly printed. The ribbon 16 is wound on two ribbon rollers 18 and 19 operated respectively by ratchets 20 and 21, which are controlled by retaining pawls 22 and 23, each retaining pawl having an arm 24 which is adapted to be operated by the adjacent end of a release bar 25, which is slidably mounted on the bed 2, and which has two sockets 26 and 27 either of which is adapted to receive a spring pressed bolt 28, which is slidably mounted in and projects from the bed 2. A lever 29 is pivoted at 30 to the release bar 25 and has projections 29' and 30' which are respectively in register with sockets 26 and 27, so that by tilting the handle 29 in one direction or the other it

may be operated to cause its projection 29' or 30' to slide the locking bolt 28 from engagement with socket 26 or 27 as the case may be, and thus permit the release bar 25 to be slid in either direction to cause either of the ends of the release bar to strike against either arm 24 and tilt either retaining pawl 22 or 23 out of engagement with its ratchet 20 or 21. At other times the spring pressed bolt 28 is yieldingly held in engagement with socket 26 or 27 and locks the release bar 25 from accidental movement. As shown in Fig. 1, the release bar 25 is at the left holding retaining pawl 22 out of engagement with ratchet 20 and allowing retaining pawl 23 to remain in engagement with ratchet 21, and the handle 29 is shown in one normal position, allowing the bolt 28 to engage in socket 27 to lock the release bar 25.

A pawl bar 31 is slidable on the bed 2 and pivoted at its ends are operating pawls 32 and 33, the pawl 32 being a pull pawl and the pawl 33 being a push pawl, each pawl being formed with a cam face 34 which is adapted to be operated by the adjacent end of the release bar 25 according as the latter is moved in one direction or the other. Coil springs 35 serve to yieldingly hold the operating pawls 32 or 33 in engagement with their respective ratchets. As shown in Fig. 1, release bar 25 has been moved to the left so that its end has disengaged pawl 32 from ratchet 20, and has permitted pawl 33 to engage ratchet 21. At each reciprocation of the bed the ribbon is actuated in the following manner: A lug 36 projects from the pawl bar 31 and near the limit of the rear stroke of the pawl bar as it is carried back by the bed the lug strikes against a projection 37 on a ribbon bar 38, which arrests further movement of the lug 36 while the bed continues its further rearward movement a short distance, sufficient to cause a relative sliding movement between pawl bar 31 and the bed, thus causing pawl 33 to actuate ratchet 21 and advance the ribbon one step. As the bed makes its rear stroke, upon the lug 36 leaving the projection 37, the pawl bar 31 is restored to normal position by a spring 39 which brings the pawl 33 behind the next tooth of ratchet 21. This actuation of the ribbon takes place at each stroke of the bed under some conditions.

It is sometimes desirable to operate the 110

machine without using the ribbon and to ink the type 14 direct by roller, and at other times in the operation of the machine when the printing operation is arrested by manually controlled mechanism to be herein described, it is not necessary to advance the ribbon until the printing operation has been performed, and I have therefore provided means for arresting actuation of the ribbon under these conditions. The ribbon bar 38 has a slot 38' which engages a pin 40 on the frame 1, thereby permitting the ribbon bar to have a longitudinal movement as well as a lateral swinging movement. The ribbon bar 38 has a Z slot 41 which engages pin 42 in the frame 1, and has pins 43 and 44, while pins 45 and 46 project from the frame 1. Under normal conditions a coil spring 46' is connected between pins 43 and 45 which holds the ribbon bar 38 to the rear so that pin 42 lies at the angle of the Z slot 41, as shown in Fig. 2. This inclined position of the ribbon bar 38 causes the projection 37 to stand in the path of movement of the lug 36, and when in this position acts to arrest movement of lug 36, and cause actuation of the ribbon. If, however, it is desired to operate the machine without using the ribbon the spring 46' may be disconnected from pins 43 and 45 and connected between pins 44 and 46, so that the ribbon bar 38 will then be held in the other position with the left end of Z slot 41 at the pin 42, thus holding projection 37 out of the path of movement of lug 36, and thereby permit of movement of lug 36 without actuating the ribbon mechanism.

A throw-off lever 48 is provided for arresting the printing operation of the machine as will be described, and the ribbon bar 38 has a projection 49 in the path of movement of the throw-off lever 48, as shown in Fig. 2, so that when the throw-off lever 48 is tilted to arrest the printing operation of the machine it will retract from projection 49 and allow the ribbon bar 38 to slide rearward, thereby moving the projection 37 so far to the rear of the stroke of the lug 36 that the lug 36 will not move far enough to engage the projection 37, and thus this tilting throw-off movement of the throw-off lever will stop the operation of the ribbon mechanism until the throw-off lever is restored, so that the ribbon will not be unnecessarily used up when the machine is not printing.

In my former application referred to, the throw-off lever 48 had a rocking motion with each reciprocation of the bed, and in the present invention I avoid this. The throw-off lever 48 when operated acts to arrest the printing of a sheet without stopping the reciprocation of the bed, this arrested condition to continue so long as the throw-off lever remains in its tilted position, and

upon being restored to normal position the printing is again resumed. As in my former patent, this is accomplished by causing the throw-off lever to rotate an eccentric support which lifts the impression roller so that the paper is not pressed against the type. This is accomplished by a sliding rack 50 which moved in one direction rotates a gear 50' and eccentric 50", elevates the impression roller to non-printing position, as shown in full lines, Fig. 1, and when moved in the other direction lowers the impression roller to the printing position shown in dotted lines. The present case is concerned only with the shifting of this rack, the mechanism operated by the said rack forming no part of the present invention, being fully described and claimed in the previous patent. The rack 50 is adjustably mounted on a rack bar 51, there being a rod 52 secured to the rack 50 and engaged by a thumb nut 53, the latter being confined between the lugs 54 on the rack bar 51, so that by turning the thumb nut 53, the rack 50 may be adjusted in either direction relative to the rack bar 51.

The rack bar 51 is normally held yieldingly in forward position by a spring 55 as shown in Fig. 2, one end of spring 55 being connected to the rack bar 51, and the other end of the spring being connected to a pin 56 which projects from the frame 1, the rack bar 51 being slotted at 57 to permit it to slide with respect to pin 56.

Two ink plates 108 are provided at opposite ends of the machine. But only one is shown. These ink plates are so arranged that they may be instantly removed or replaced without danger of misplacement, the construction being such that when the ink plate is replaced, it naturally finds a perfect seat, and thereby rests at the proper elevation so that it is impossible through carelessness in replacing the ink plate to cause it to stand at too high an elevation, such that it would strike and damage the machine when operated. This is accomplished by constructing the ink plate with a stem 109, the lower end of which has a plurality of radial teeth 110, the lower faces of which are beveled as shown in Figs. 5 and 6. The teeth 110 are adapted to engage in radial notches 111 formed in the head 112 of a rotating post 113. Between the notches 111 the intervening portions 114 are provided with beveled faces 115, which are received in corresponding notches formed between the teeth 110. It will be apparent that owing to the beveled ends of the teeth 110 and 114 that the beveled faces thereof will cause a partial rotation of the stem 109 owing to the weight of the ink plate 108 if it be placed upon the head 112 in such an angular position that the teeth 110 do not perfectly register with the

notches 111. This rotation will gradually turn the stem 109 into such a position that the teeth 110 will be moved into register with notches 111, whereupon the stem 109 and ink plate 108 will settle into normal position with the teeth 110 engaging in notches 111. This construction insures that the ink plate 108 will automatically descend to its proper level even though it be carelessly placed in position.

The stem 109 is revolvably mounted in a socket 116, which is formed at the end of the U bar 117 projecting from the traveling bed 2. The socket 116 is formed with an internal shoulder 118', upon which rests the head 112 of the post 113, thereby supporting the latter revolvably. Secured to the post 113 is a ratchet 118 which is engaged by two spring pressed pawls 119, which are pivotally mounted on a pawl lever 120, which is journaled concentrically with the post 113, and adapted to oscillate with respect thereto, and when oscillated to cause its pawls 119 to turn the ink plate 108. The pawls 119 are so arranged that when one of them engages a tooth of the ratchet, as clearly shown in Fig. 2, the other one will be half way between two other teeth. This enables ratchet teeth to be employed of twice the size required for a given minimum stroke. Each pawl 119 when actuated will turn the ratchet a distance of one half a tooth. In addition to this advantage, this spacing of the pawls insures an engagement of a pawl. In order to guide and support the pawl lever 120, a cross bar 121 is provided, and a loop 122 projects from the pawl lever 120, and slides on the cross bar 121. The pawl lever 120 has a finger 123, which at the end of each printing stroke of the bed is brought into contact with a roller 124 mounted on frame 1, which acts against the finger 123 to swing the pawl lever 120 in a direction to cause the pawls 119 to retract and engage succeeding teeth, and as the bed 2 commences to move rearwardly an extension spring 125 retracts the pawl lever 120 and causes the pawls 119 to actuate the ratchet 118 and turn the ink plate 108. The roller 124, as shown in Fig. 4, is mounted on a bail 124' which is pivoted on a shaft 126 mounted in a bracket 127, and a coil torsion spring 128 is arranged to hold the bail 124' normally in a vertical position so that the roller 124 will stand in the path of movement of the finger 123. This construction allows the roller 124 to yield from any object which it might strike accidentally during the rear stroke of the bed.

The ink plate 108 is inked as it passes underneath an inking roller 125'. The roller 125' is supplied with ink from an intermediate ink roller 126', which is mounted in the lower end of an ink fountain 127' shown in detail in Fig. 3. The ink fountain

127' has an inclined bottom 128' and a distributing roller 129' floats within the ink fountain and against the roller 126' and serves to distribute ink from the fountain on the roller 126'. The roller 129' thus takes a natural position, and its weight gives the necessary pressure required for its distributing function. This method of floating the roller enables it to accommodate itself to any ununiformity and also enables it to be instantly removed when it is desired to clean the fountain, thus enabling the fountain to be very quickly and readily cleaned, as all of the parts are rendered accessible and crevices or places where ink may lodge are almost entirely eliminated. The bed of the ink fountain rests upon a cross bar 130 and one end of a bolt 131 is attached to the cross bar 130 and the bolt extends slidably through a flange 132 on the end of the ink fountain and a thumb nut 133 is arranged on the bolt 131 to adjust the ink fountain toward the roller 126', while a spring 134 is arranged between the cross bar 130 and the flange 132 to press the ink fountain in the opposite direction, and thus hold it steadily in the position in which it is adjusted by the thumb nut. This adjustment is independent of and in addition to the automatic floating adjustment of the roller 129' hereinbefore described. The side walls 135 of the ink fountain are notched to fit over the shaft 136 of the ink roll 126' and allow the proper adjustment of the edge 137 of the ink fountain with respect to the roll 126'.

What I claim is:

1. In a printing machine, an ink plate having a stem formed with radial teeth on its end, a post having radial notches adapted to receive the radial teeth, said teeth having beveled ends, the portions of said post lying between the notches in the post having beveled ends, for automatically turning the stem to bring its teeth into register with the notches in the post.

2. In a printing machine, an ink plate, a rotatable post with which the ink plate is detachably connected, a ratchet on said post, a lever pivoted concentric with the ink plate and traveling bodily therewith, pawls on said lever engaging said ratchet, a traveling bed supporting the foregoing elements, said pawl lever having a finger, and stationary means in the path of movement of said finger for swinging said pawl lever when the finger is moved into engagement with said stationary means.

3. In a printing machine, a traveling bed, a U bar mounted thereon, a vertical post rotatable in the U bar, an ink plate detachably connected to said post, a ratchet, a pawl lever pivoted on the U bar concentric with the ink plate, a pawl carried by said pawl lever and engaging said ratchet, said pawl lever having an offset finger, and sta-

tionary means in the path of movement of said finger.

4. In a printing machine, a traveling bed, a U bar carried by the bed, a post rotatable in the U bar, an ink plate detachably mounted on said post, a ratchet on said post, a pawl lever pivoted concentric with said post, pawls on said lever engaging said ratchet, a spring connected between the U bar and pawl lever for moving the lever in one direction, said pawl lever having a finger and a stationary roller in the path of movement of said finger.

5. In a printing machine, a traveling bed, a U bar carried by the bed, a post rotatable in the U bar, an ink plate detachably mounted on said post, a ratchet on said post, a pawl lever pivoted concentric with said post, pawls on said lever engaging said ratchet, a spring connected between the U bar and pawl lever for moving the lever in one direction, said pawl lever having a finger, a stationary roller in the path of movement of said finger, pivoted means on which said roller is mounted, and spring means for yieldingly holding said pivoted roller supporting means in normal position in the path of movement of said finger.

6. In a printing machine, a traveling bed, a U bar carried by the bed, a post rotatable in the U bar, an ink plate detachably mounted on said post, a ratchet on said post, a pawl lever pivoted concentric with said post, pawls on said lever engaging said ratchet, a spring connected between the U bar and pawl lever for moving the lever in one direction, said pawl lever having a finger, a stationary roller in the path of movement of said finger, a cross bar on the U bar, and a loop on the pawl lever slidably engaging said cross bar.

7. In a printing machine, an ink fountain

comprising an inclined bottom with side walls, an inking roller, a cross bar under the side walls, said inclined bottom being slideable on the cross bar toward and from said inking roller, and a floating roller resting upon the inclined bottom.

8. In a printing machine, an ink fountain comprising an inclined bottom with side walls, an inking roller, a cross bar under the side walls, said inclined bottom being slideable on the cross bar toward and from said roller, and a floating roller resting upon the inclined bottom, a screw with one end secured to said cross bar, the inclined bottom having a flange through which said screw extends, a thumb nut on the screw bearing against said flange, and a spring for moving said inclined bottom away from said first mentioned roller.

9. In a printing machine, an ink fountain comprising an inclined bottom with side walls, an inking roller, a cross bar under said side walls, said inclined bottom being slideable on the cross bar toward and from said roller, and a floating roller resting upon the inclined bottom, a screw with one end secured to said cross bar, the inclined bottom having a flange through which said screw extends, a thumb nut on the screw bearing against said flange, and a spring for moving said inclined bottom away from said first mentioned roller, another roller below the first named roller, said side walls being notched to slide above the shaft of the first mentioned roller.

Signed at Los Angeles, California this 2d day of January 1914.
